UNITED STATES PATENT OFFICE.

ALLEN B. WILDER, OF ST. LOUIS, MISSOURI, ASSIGNOR TO WILDER PATENTS COMPANY,
OF ST. LOUIS, MISSOURI, A CORPORATION OF MISSOURI.

GAME-BOARD AND SPINNER DEVICE.

1,300,315.

Specification of Letters Patent.

Patented Apr. 15, 1919.

Application filed December 4, 1917. Serial No. 205,276.

To all whom it may concern:

Be it known that I, ALLEN B. WILDER, a citizen of the United States, and a resident of the city of St. Louis and State of Missouri, have invented a new and useful Improvement in Game-Boards and Spinner Devices, of which the following is a specification.

This invention relates to games of the kind in which the players are represented by counters which are moved over a playing board and has for its object to devise a game which will provide entertainment and at the same time tend to make the players proficient in arithmetic. The invention consists in a playing board which is divided into zones representing animate and inanimate objects which the players try to capture.

The invention also consists in a spinner device having a plurality of rotative elements and a plurality of numbers arranged in concentric bands. Further objects and details of the invention appear hereinafter, and what is claimed as the invention appears in the appended claims.

In the drawings, which form a part of this specification and in which like reference characters indicate like parts in the several views,

Figure 1 is a plan view of the spinner device;

Fig. 2 is a side elevation of the same; and

Fig. 3 is a plan view of a game board embodying the invention.

The dial 1 of the spinner apparatus comprises three series of numbers arranged in concentric circular bands 2, each of which is different in color from the other two, or differentiated from them in some other manner. Radial lines divide the bands 2 into arcs, in each of which is a number. These numbers are arranged so that each number of one series is exactly divisible by the corresponding number of one of the other series, and so that each number in one series is at least as large as the corresponding number in each of the other series, and in most instances larger than either of them.

In the drawing, each number of the series in the outermost band is exactly divisible by the corresponding number of the series in the innermost band. Each number of the series in the outermost band is at least as

large as the corresponding number of each of the other series.

A pointer 3 turns on a fixed pivot piece 4 at the center of the circular bands 2. The pointer 3 is spaced away from the dial by a washer 5. A circular disk 6 is pivoted on the pivot 4 and rests loosely on the pointer 3. This arrangement affords a kind of frictional engagement between the pointer and the disk that will cause them to move together under some conditions and not under others. The disk 6 is divided into differentiated sectors. These sectors are marked to indicate respectively addition, subtraction, multiplication, and division, or some of them. The location of the disk relatively to the pointer when both stop turning determines whether addition, subtraction, multiplication or division is necessary to ascertain the result of the spin. If the head of the pointer is in the sector marked "addition", addition is necessary, and so on. Space is afforded in the corners of the dial for legends indicating which numbers are to be added together, which is the minuend and which the subtrahend, which is the multiplicand and which the multiplier, and which is the dividend and which the divisor.

The game board shown in Fig. 3 comprises a plurality of zones, each representing an animal. Each zone contains the name of an animal, together with a number indicating its value in the game. Each zone also contains a plurality of other numbers whose purpose appears hereinafter. A continuous path traverses the zones. Side paths afford more direct routes between certain points of the main path. The route is indicated by arrows. These paths represent the path taken by a hunter in search of game. Stopping points of two kinds are marked on the paths. In the drawings, red circles and black circles are used.

Each player is represented by a counter which is moved along the paths in the direction indicated by the arrows. The spinner apparatus is used in the manner previously described. For the first or moving play, the position of the disk is disregarded, the outermost number pointed at by the pointer is divided by the innermost and the counter is moved the number of circles indicated by the quotient. If the counter stops

on a black spot, the player's turn is over. If it stops on a red spot, the player is said to "sight" game and has a chance to see if he can hit the animal of the zone in which 5 the counter is located. He spins the pointer a second time, and adds, subtracts or multiplies, according to the position of the disk relative to the pointer when they stop turning. If the number or numbers so obtained 10 appear in the zone in which the counter is located, the player is said to have killed the animal and scores the number of points indicated as the value of that animal. When a counter stops on a spot where two paths 15 diverge, the shorter path is taken at the next play.

Game boards and spinner devices of the kind described afford opportunities for practice in arithmetic. It is obvious that 20 changes may be made both in the playing board and in the spinner device without departing from the invention, and I do not wish to be limited to the particular constructions shown.

25 I claim as my invention:

1. A spinner device comprising a dial bearing series of numbers arranged in concentric bands, a pointer pivotally mounted at the center of said bands, and a disk concentric with said pointer and having frictional engagement therewith, said disk being divided into differentiated sectors.

2. A spinner device comprising a base board bearing series of numbers in concentric bands, and a plurality of indicator elements pivotally mounted at the center of said bands and having frictional engagement with each other, whereby they rotate differentially together when one of them is 40 spun.

3. A spinner device comprising a dial bearing series of numbers in concentric bands, each number in one band being exactly divisible by the corresponding number in another band, a pointer pivotally mounted at the center of said bands, and a disk concentric with said pointer, said disk being divided into differentiated sectors.

4. A spinner device comprising a dial bearing series of numbers arranged in concentric bands, each number in the outermost band at least as large as the corresponding number in each of the other bands, a pointer mounted on a pivot at the center 55 of said bands, and a disk mounted on said pivot to turn differentially with said pointer above said pointer, said disk being divided into sectors.

60 5. A spinner device comprising a dial bearing a plurality of series of numbers in concentric bands, each number in one band

being exactly divisible by the corresponding number in another band, and each number in one band being at least as large as the corresponding number in each of the other bands, a pointer pivotally mounted at the center of said bands, and a disk concentric with said pointer and having frictional engagement therewith, said disk being divided into sectors.

70 6. A spinner device comprising a dial bearing series of numbers in concentric bands, a pointer mounted on a pivot piece at the center of said bands, and a disk mounted on said pivot piece to turn differentially with said pointer, said disk being divided into sectors, said sectors being marked respectively to indicate addition, subtraction and multiplication.

7. A playing board for games of the kind described comprising suitably indicated zones, each of which contains the name of an object of value in the game, and a continuous path traversing each of said zones, said path comprising spaces of red interspersed with spaces of black.

8. A playing board for games of the kind described comprising suitably indicated zones, each of which contains the name of an object of value in the game, a number 90 indicating its value in the game and a plurality of other numbers, and a continuous path traversing each of said zones, said path comprising spaces of one color interspersed with spaces of another color.

9. The combination with a playing board comprising zones and a continuous path traversing said zones, of a spinner device comprising a plurality of bands bearing numbers and a plurality of indicator elements pivotally mounted at the center of said bands, and having frictional engagement with each other, whereby the spinning of one of said elements causes the other to spin part of the distance with it, said spinner device determining the distance the player moves along said path.

10. The combination with a playing board comprising suitably indicated zones, each bearing a plurality of numbers, and a continuous path traversing said zones, of a spinner device comprising a plurality of circular bands bearing numbers, and a plurality of indicator elements pivotally mounted at the center of said circular bands, some 115 of the numbers indicated by said indicator elements being the same as numbers in the zones.

Signed at St. Louis, Missouri, this 28th day of November, 1917.

ALLEN B. WILDER.
